UNITED STATES PATENT OFFICE.

WILLIAM McCALLUM, OF YONKERS, NEW YORK, ASSIGNOR TO THE BIGELOW CARPET COMPANY, OF CLINTON, MASSACHUSETTS.

DESIGN FOR A CARPET.

SPECIFICATION forming part of Design No. 14,363, dated October 23, 1883.

Application filed August 23, 1883. Term of patent 3½ years.

To all whom it may concern:

Be it known that I, WILLIAM McCALLUM, of Yonkers, in the county of Westchester and State of New York, have invented and produced a new and original Design for a Carpet, of which the following is a full description, in connection with the accompanying photograph, which represents a face view of my new design for a carpet.

10 This invention relates to a new ornamentation of carpets and analogous fabrics.

In the accompanying photograph are shown a series of groups of flowers, A, B, and C, between which are groups, D, of leaves, and also branches E, F, G, and H, as shown.

15

I claim—

The design for a carpet, the same consisting of the figures A B C D E F G H, substantially as shown.

WILLIAM McCALLUM.
